UNITED STATES PATENT OFFICE.

LOUIS W. GATES, OF DETROIT, MICHIGAN, ASSIGNOR TO TERNSTEDT MANUFACTURING CO., OF DETROIT, MICHIGAN, A CORPORATION OF MICHIGAN.

WINDOW REGULATOR.

1,408,879.

Specification of Letters Patent. Patented Mar. 7, 1922.

Application filed September 7, 1920. Serial No. 408,480.

To all whom it may concern:

Be it known that I, LOUIS W. GATES, a citizen of the United States, residing at Detroit, in the county of Wayne and State of Michigan, have invented certain new and useful Improvements in Window Regulators, of which the following is a specification.

This invention relates to window regulators, and has for its object a regulator which comprises simply an arrangement of levers which may be secured to one side of the window well and which is calculated to raise the window by multiplication of movement of the primary lever. The primary lever can be actuated by a few turns of a crank handle—in the arrangement illustrated, about three and a half.

The arrangement gives all the advantages of an easy lift that is ordinarily afforded by a chain drive regulator and eliminates many of its disadvantages, among which is looseness and cost of construction. These advantages will better appear after a detailed description has been given.

In the drawings,—

The figure shows the window regulator in elevation, showing the levers in two positions. The upper position is the position the parts assume when the window is completely raised. The lower position is the position the parts assume when the window is completely lowered.

a designates the window posts; *b* the usual lock board; while the dotted lines *c* indicate the bottom rail of a window. *d* represents a circular supporting plate and *e* the crank handle pivoted thereon, to which is attached a plurality of pins *f* engaging the teeth of the segment *h*. The pins *f* form the driving member. The segment *h* is part of the lever *i*, which is the primary lever and which is fulcrumed at *j*. A coiled counterbalancing spring *k* is attached at *l* to this primary lever and tends to resist the downward movement of the window to store energy to help lift it.

The primary lever *i* is attached at its end to the draft link *m* which has its lower end engaging with one corner of the triangular plate *n*. A second corner of the triangular plate *n* pivots the arm *o*, the opposite end of which is pivoted at *p* to a toggle arm *r*. This toggle arm *r* is pivoted to the lower rail *c* of the window. The companion toggle arm is designated *s* and is pivoted to the

toggle arm *r* and to a side bracket or anchoring member *t* that can be secured to the side of the window post.

The action is simply this: At the beginning of the ascent the operation is really that of a triple system of levers, for instance, we have the main lever *i* which is fulcrumed at *j*, whose power end is the teeth *h* and whose load end is at the pivot 60 of the draft link *m*. The draft link *m* then transfers the load from the second lever which happens to be the plate *n* having its fulcrum at *x* and its load at *u* and its power application at *v*. The arm *o* then transfers 70 the load from the toggle arm *r* which pivots at *w* and has its load at *y* and its power application at *p*. It will be noted that in each of these three lever cases there is an adverse leverage, that is, the load arm of 75 the lever is longer than the power arm. This consequently simply results in a multiplication of movement for a given turn of the segment *h*, and that is what the triple lever arrangement is for.

As the window ascends, the point *v* comes substantially under the point *u* and substantially eliminates the plate *n* as a multiplying lever, but now the plate *n* begins to draw on the toggle arm *s* at the point 80 *x* and converts this toggle arm into a multiplying lever. In fact, until the window is almost three-quarters closed, the various levers swing around so that really the only effective multiplying ones are the primary 85 lever and the toggle arms *s*, but as the window gets to about the last quarter of its rise, the action is really a lazy-tong action, as will be evident from comparing the two 90 positions of the lever shown in the drawings. The toggle arms *s* and *r* in the upper position are substantially on a straight or center line or slightly thereover, while that portion of the plate *n* included between the pivot *x* and the pivot *u*, which is in effect a toggle arm, and the toggle arm *o* 95 approach a straight line but do not quite reach it. That portion of the plate between the points *x* and *u* and the link *o* might be referred to as auxiliary toggle arms for that 100 is what they really are. They are auxiliary toggle arms pivoted to the main toggle arms *s* and *r*. These two sets of toggle arms form the lazy-tongs. As already indicated, the 105 action is in the effect first that of a plurality of multiplying levers. This is the action through substantially the first three-

quarters of the movement of the window upward. As the last quarter is reached the draft link *m* draws upon the plate *n* so as to tend to cause the two sets of toggle arms 5 to straighten out by drawing in on the knee of the set of small toggle arms. This does not multiply the movement but rather decreases it. However, the toggle arm or lever *s* has now come to substantially horizontal 10 position, where the vertical component of its movement is very much greater than when it starts to move. Consequently the rise of the window is substantially uniform. However, the exact uniformity is not obtained all 15 through the travel of the window for this arrangement of levers results in a slightly slower movement when the window is first started and a slightly slower movement as the window finally closes. This slower 20 movement, of course, means that less force is required to accomplish it and hence the lifting starts out easily and the window closes with sort of a snap as the operator continues the same force in turning the handle at the finish, resulting in slightly speeding up the movement and serving to cause the main toggle arms to snap by their center and the weather rail and weatherstrip (not shown) to jam together. 25

30 It will be noted that there is a stop 1 struck out of the toggle arm *s* and the shoulder 2 on the end of the toggle arm *r*. These engage in the uppermost position to prevent the main toggle arms passing much beyond 35 their straight line position. The effect of this is important as it locks the window in its uppermost position against any effort tending to lower it applied to the window. The thrust of such an effort is substantially 40 on the dead center line of the toggle arms or else tends to break them in the direction in which the stops prevent any further movement.

It will be evident from the above description 45 that although the exact explanation of the levers and the respective mechanical advantages is more or less complicated, the device is very simple to build from a manufacturing standpoint and yet most efficient. 50 The levers are all practically nothing but strap metal that can be stamped out in great quantities at little cost. The pivots are simply rivets.

The device may be accurately assembled to 55 the job simply by placing the supporting plate *d* in the mortise made for it in the lock board. The levers are then moved until the larger toggle arms snap by their center and rest against the stops. The window is then 60 raised to its upper limit. The bracket *t* is then run along the side of the window post and fastened by screws wherever the two main toggle arms located in their straight line position brings it.

65 It will be noticed that in effect the plate *n*

is a bent lever of the third order during the initial stages of the raising of the window from the bottom of the well. I, therefore, refer to it in the claims as a lever of the third order. I have found it expedient in 70 the claims to refer to a number of the elements by their reference characters. This is not intended as a limitation but merely in the interest of clearness in view of the fact that in this case there are such a large number of similar elements that it is hard to otherwise properly identify them. 75

What I claim is:

1. In a window regulator, the combination of a supporting plate, a driving member 80 journaled thereon, a lever anchoring member for attachment to a window frame, and a lever system for connecting the driving member, the anchoring member and the bottom of the window, comprising a primary lever *i*, a draft link pivoted thereto, and two sets of toggle arms, the main set being between the anchoring member and the bottom of the window and the auxiliary set pivoted to these toggle arms and connected 85 with the draft link. 90

2. In a window regulator, the combination of a supporting plate, a driving member journaled thereon, a lever anchoring member for attachment to a window frame, and 95 a system of levers between the driving member, the anchoring member and the bottom of the window, comprising a primary lever *i*, a draft link, and two sets of toggle arms, one a main set engaging between the anchoring 100 member and the bottom of the window, the other a smaller set secured to the larger toggle arms and including a triangular member to which is attached to the draft link *m*.

3. In a window regulator, the combination 105 of a supporting plate, a driving member journaled thereon, a lever anchoring member adapted for attachment to the side of a window post, and a system of levers connecting the anchoring member, the driving member 110 and the bottom of the window, comprising a primary lever and gear segment *i*, a draft link *m*, a triangular plate *n* connected therewith, a companion toggle arm *o* together with two larger toggle arms *s* and *r* to which the latter two members are pivoted and which engage between the anchoring member and the bottom of the window. 115

4. In a window regulator, the combination 120 of a supporting plate, a driving member journaled thereon, and a side bracket for attachment to a window post, and a system of levers for connecting said bracket, driving member and the bottom of the window, comprising a primary lever *i*, a draft link *m*, a triangular plate *n* connected with the draft link, a companion toggle arm *o* and two larger toggle arms *s* and *r* to which the smaller toggle arms are pivoted and which are pivoted to the side bracket and the 125 130

- bottom of the window, said two larger toggle arms being provided with a stop and a shoulder to prevent their breaking in one direction and hence locking the window in 5 its uppermost position against effort tending to break the toggle arms through an effort on the window.
5. In a window regulator, a lever anchoring member for attachment to a window 10 frame, and a lever system between the anchoring member and the bottom of the window comprising two sets of toggle arms, the main set being between the anchoring member and the bottom of the window and the 15 auxiliary set pivoted to these toggle arms, and means for pulling upon said auxiliary set of toggle arms for swinging the main set of levers from a point below said anchoring member to a position above said anchoring member and for straightening said sets 20 of toggle arms to raise the window.
6. In a window regulator, the combination 25 of a lever anchoring member for attachment to a window frame, a lever system for connecting the anchoring member and bottom of the window, comprising two sets of toggle arms, the main set being located between the anchoring member and the bottom of the window and the auxiliary set pivoted to 30 these toggle arms, one of said auxiliary set of toggle arms provided with an extended portion which forms in effect a bent lever of the third order (specifically the plate *n*), and means for pulling upon said bent lever 35 of the third order to swing said levers above
- their fulcrum on the lever anchoring member and to straighten or fold the auxiliary toggle arms for the purpose of raising or lowering the window.
7. In a window regulator, the combination 40 of a lever anchoring member for attachment to the side of a window post, a pair of toggle arms, one pivoted to the anchoring member and the other pivoted to the bottom of the window and the said toggle arms arranged to swing above and below their fulcrum on said anchoring member, a second set of auxiliary toggle arms, one pivoted to each of the first-mentioned toggle arms, the auxiliary toggle arm which is pivoted to the 45 main toggle arm secured to the anchoring member being in effect also a bent lever of the third order (specifically the plate *n*), and means for engaging the bent lever of the third order for swinging said toggle arms 50 above and below their point of fulcrum on the anchoring member and for straightening or folding the auxiliary toggle arms 55 to raise or lower the window.
8. In a window regulator, a lever anchoring member for attachment to the side of a window frame, and a lever system including a plurality of levers arranged in lazy tongs relation and adapted to pivot all together as 60 a unit on said fulcrum and swing from a position below said fulcrum to a position above in straightening out and vice versa in folding up.

In testimony whereof I affix my signature.
LOUIS W. GATES,
